UNITED STATES PATENT OFFICE.

HUGO O. STAMP, OF MILWAUKEE, WISCONSIN.

LOADING-MACHINE FOR CONCRETE-MIXERS AND THE LIKE.

1,265,131.

Specification of Letters Patent.

Patented May 7, 1918.

Application filed March 23, 1916. Serial No. 86,059.

To all whom it may concern:

Be it known that I, HUGO O. STAMP, a citizen of the United States, and resident of Milwaukee, in the county of Milwaukee and 5 State of Wisconsin, have invented certain new and useful Improvements in Loading-Machines for Concrete-Mixers and the like; and I do hereby declare that the following is a full, clear, and exact description thereof.

10 The present invention relates to new and useful improvements in conveying apparatus wherein the various conveyer sections are relatively movable to engage the material to be conveyed, and the invention is 15 more particularly directed to the provision of a loading machine adapted for use in connection with concrete mixers.

The present invention is directed to the provision of a machine similar in general 20 nature to the loading machine embodied in my application for patent filed June 23, 1915, Serial No. 3969 and has for its primary object to improve the structure and efficiency of such machines, more particularly with a 25 view to lightening their general structure and adapting them for an exceedingly wide range of work.

More specifically, an important object resides in the provision of a machine wherein 30 the material conveyed is subjected to a minimum lifting movement to effect its discharge into the skip of a concrete mixer or other receptacle, to procure an economy of power in operating the machine and further to permit the use of a relatively light structure of machine.

In view of the relatively great narrowness and length of a machine of this character, the various strains imparted thereto during 40 its operation would tend to shift the machine laterally of its desired central position with respect to the piles of aggregate. It is therefore a further object of the present invention to provide an arrangement whereby in 45 operation the major portion of the machine rests directly on the ground to thus procure a firm engagement preventing any possibility of shifting movement, and in view of the essential feature of mobility in machines 50 of this nature, it is in this connection further an object to provide means for procuring a wheeled support for the machine whereby it may be readily adapted for the frequent shifting movements necessary in 55 operation and to adapt it for its transportation generally.

The present invention contemplates the provision of main conveyer members and lateral conveyer members longitudinally movable with respect thereto and arranged 60 to discharge thereon, and it is further an object of the invention to provide a structure whereby the lateral conveyer members may each engage an elongated pile of aggregate throughout its entire transverse area, 65 so that substantially the entire content of the pile may be conveyed upon movement of the lateral conveyer member thereagainst in a single direction of movement.

A further object of the invention resides 70 in the provision in a conveying apparatus of the type described, of a structure wherein the conveyer elements of each longitudinal conveyer member and the corresponding lateral conveyer are connected on a single common endless chain so that a single drive 75 means suffices for both conveyer members to procure an exceedingly simple and consequently operatively economical structure.

A still further object of the invention, 80 which is partially compassed in the fulfillment of the foregoing object is to provide a machine wherein the main conveyer structure is exceedingly narrow so as to permit 85 operation of the machine between piles of aggregate which are relatively close together.

In some concreting operations it may be found expedient to arrange the aggregate in other than necessarily parallel piles such as are employed in road building, and to 90 adapt the present apparatus for use also under these conditions. It is therefore further the object of the invention to provide a structure wherein the main conveyer members and their lateral conveyers are mounted 95 for horizontal pivotal movement with respect to the body of the machine and in this connection it is a more specific object to provide a means for procuring a wheeled support of the main conveyer members when 100 it is desired to move said members pivotally, and also when it is desired to transport the machine.

In connection with this feature of relative horizontal movement of the main conveyer members, it is more specifically an object to provide a drive mechanism for the conveyer members, which automatically adjusts itself for operation in the various desired positions of the conveyer members. 105

A still further object resides in the provision of a machine which may be manipu-

lated for its conveying and measuring operations from a single point and by a single operator.

A more detailed object in connection with the lateral conveyer members is to provide a mounting therefor whereby said members are permitted a limited degree of vertical pivotal movement to compensate for irregularities of the ground over which the said conveyer members travel and also to compensate for relative movement of the main conveyer members in lifting said members to procure a wheeled support therefor as heretofore mentioned.

15 A further object in this connection resides in the provision of a mounting for the lateral conveyer members which permits them to swing horizontally, and to be operated in such swung position to provide for operation of the members in a restricted space.

20 A still further object in connection with the lateral conveyer members is to procure a scraping or digging action of the conveyer elements with respect to the piles of aggregate and to accomplish this the invention contemplates the provision of lateral conveyer members including each a conveyer bed plate and a toothed scoop plate conveyer slidable thereover.

25 With the above and other objects and advantages in view, the invention resides more particularly in the novel combination, arrangement and formation of parts more particularly hereinafter described and particularly pointed out in the appended claims.

In the drawings

Figures 1 and 1^a show a side elevational view of a preferred embodiment of the present invention;

30 Fig. 2 is a transverse sectional view through the body portion of the machine at the pivots of the main conveyer members, this view being taken on a plane indicated by the lines 2—2 of Figs. 1 and 3;

35 Fig. 3 is a top plan view of the forward portion of the machine;

Fig. 4 is a top plan view of one of the lateral conveyer members and the adjacent portion of the respective main conveyer member;

40 Fig. 5 is a vertical sectional view taken through the lateral conveyer member on the line 5—5 of Fig. 4;

Fig. 6 is a transverse sectional view there-
45 through on the line 6—6 of Fig. 4;

Fig. 7 is a detail sectional view taken transversely through one of the conveyer plates, and showing the means of attachment thereto to the conveyer chain;

50 Fig. 8 is a side elevational view of one of the conveyer plates;

Fig. 9 is a fragmentary sectional view through the work engaging edge of one of the conveyer plates.

55 Fig. 10 is a top plan view of the hopper

portion of the machine, showing the adjusting features thereof;

Fig. 11 is a transverse sectional view through one of the windlass drums;

Fig. 12 is a top plan view of the improved machine in diagrammatic outline, and showing in dotted lines the lateral position adapted to be assumed by the main conveyer members.

Referring now more particularly to the accompanying drawings, the embodiment of the present invention therein shown comprises a wheeled head or body truck A carrying suitable hoppers and a pair of main conveyer members B arranged to discharge into the hoppers and pivotally connected with the truck whereby the said members may be swung horizontally. Longitudinally movably connected with each main conveyer member is a laterally extended conveyer member C. The main and lateral conveyer members comprise essentially conveyer beds, and the conveyers proper comprise each a plurality of conveyer elements carried on a single endless chain which is looped longitudinally with respect to a main conveyer member, and provided with a lateral loop operating in conjunction with the corresponding lateral conveyer member.

Entering now more specifically into the structure of the body truck of the machine, said truck comprises a frame 20 supported by the wheeled axles 21 and carrying an engine 22 of any desired type, which provides the motive power for the conveyers. Upstanding at the forward corners of the frame are a pair of standards 23 which have their upper ends rearwardly curved and connected by a transverse beam 24 and supported between the intermediate portions of the standards are a pair of hopper sections, 25 arranged to discharge at the forward end of the truck. Adjacent the tops of the hoppers the standards carry forwardly extending brackets which carry a platform 26 on which the operator stands when operating the machine. For closing the hoppers when desired, a closure gate 27 is hinged to the lower edges of the discharge mouths of the hopper, and pivoted to this gate outwardly of and adjacent its hinge connection is a link 28 which extends to an angular lever 29 pivoted at its angle to the platform and coacting with a notched segment 30 carried by the platform whereby the gate may be held in either open or closing position.

The pivots of the main conveyer members comprise upper vertical pivot shafts 31 carried by the end portions of the transverse top beam 24, and lower vertical pivot shafts 32 carried by a transverse sill 33 of the frame 20 and by a beam 34 spaced thereabove and having its ends forwardly bent and attached to the intermediate portions of the standards 23, this structure providing

ample clearance for the hoppers which extend between the forwardly directed ends of the same beam. The shafts 31 and 32 at each side of the machine are in vertical alignment.

- The lower pivot shafts 32 also form part of the drive mechanism for the conveyer members, and this drive mechanism includes vertical sprocket arbors 35 each having its laterally turned end portions journaled on a shaft 32 adjacent the beam 34 and sill 33. Intermediately journaled in these arbors are horizontal stub shafts 36 on each of which is fixed a sprocket wheel 37 and a beveled gear-wheel 38 disposed inwardly of this sprocket-wheel, this gear wheel meshing with an idle gear-wheel 39 carried on the corresponding pivot shaft 32 and each of these idle gear wheels meshing in turn with loose gear wheels 40 mounted on the ends of a transverse shaft 41 which is journaled in sleeve brackets 42 fixed on the pivot shafts 32. This shaft 41 has a sprocket connection 43 with the engine 22. For imparting power to the wheels 40, friction clutches 44 are splined on the end portions of the shaft and are engageable with the gears 40. Thus upon shifting the friction clutches into and out of mesh with the gears, each main conveyer member together with its lateral conveyer may be independently controlled.

Inasmuch as any conventional means may be employed for shifting these clutches, no specific means has been shown.

Carried by the upper ends of the standards 23 is a transverse shaft 45 which carries at its end portions certain hereinafter described pairs of windlass drums for manipulating the conveyer members.

Inasmuch as each main conveyer member and its lateral conveyer member is identical in structure, a specific description of only one structure will be described and the materials used will apply equally to each structure.

Each main conveyer member comprises a conveyer bed 46 and intermediate and upper conveyer tracks 47 and 48 respectively and the bed and tracks are connected to form a frame by a plurality of spaced standards 49 having their lower ends bent under the conveyer bed to form ground engaging portions and having their upper ends bent inwardly and carrying inwardly extending brackets 50 having their free ends upwardly offset to carry one section of the upper track bed, this track bed as shown comprising plates angular in cross section with their adjacent edges spaced to define a groove in which slides the chain portion of the conveyer proper. The intermediate track 47 is carried by suitable brackets 51 intermediate secured to the standards.

At the outer end, the main conveyer frame 52 includes a rectangular frame 53 and pivoted

to this frame is a wheeled standard 53 carrying the ground wheel 54, this standard being of a length greater than the distance between its pivots and the ground whereby upon swinging the standard inwardly, the outer end of the main conveyer member will be lifted from the ground. At the inner end portion of the conveyer member, the conveyer bed and the upper track bed are inclined upwardly in substantially parallel relation, and connected by suitable cross braces 55 and the extremity of the conveyer bed is directed laterally at 56 to discharge into a hopper. This end of the conveyer bed is pivotally supported on a pivot shaft 57 carried by one bifurcated arm of a bracket 58 which has its other arm bifurcated to embrace the beam 24, and carrying bearings in which engage the ends of the respective upper pivot shaft 31. Thus the entire structure is mounted for both vertical and horizontal pivotal movement.

A guide frame for the upwardly directed inner end portion of the conveyer frame is provided which also serves to carry the adjacent end of the conveyer proper. This frame includes a pair of laterally divergent bars 59 extending upwardly from each end portion of the arbor 35 and the bars at each side are convergent and have their ends secured to a respective one of a pair of head plates 60 at the sides of the conveyer frame, these plates being connected under the frame by a suitable spacer bolt 61. Extending upwardly in divergent relation from each head plate is a pair of bars 62, the forward of these bars having their upper ends converged and secured to the bracket 58 and the rearward bars having their upper ends connected with the respective rear ends of a pair of top bars 63, said rear ends of these top bars being converged and connected and the forward ends of the bars being also converged and connected through the medium of the bracket 58. Transversely journalled carried by the bars 63 at the upper end of the conveyer bed is a shaft 64 on which is mounted the drive conveyer sprocket wheel 65 about which is trained the conveyer chain 66. Carried on the end of the shaft 64 is a sprocket wheel 67 which is connected by a sprocket chain 68 with the sprocket wheel 37 of the sprocket arbor, this sprocket chain being guided in its intermediate stretches by idlers 69 carried by the spacing bolts 61 and 110 by certain of the bars 62. Extending rearwardly from each of the head plates 60 is guide bar 70 having its rear end inwardly offset to slidably engage the sides of the conveyer bed to guide the same in its vertical movements.

For lifting the main conveyer member to provide a wheeled support therefor whereby it may be swung to the position indicated in dotted lines in Fig. 12 and whereby the en-

tire machine may be afforded a wheeled support to facilitate its transportation, a windlass drum 71 is mounted on one end of the windlass shaft 45, and trained about this drum 5 is a cable 72 which extends rearwardly from the top portion of the drum and is extended adjacent a guide pulley 72^a on the respective pivot shaft 31 round about sets of pulleys 73 and 74 secured respectively to the rear 10 ends of the bars 63 and to the main conveyer, adjacent its upwardly directed end portion, the cable being finally secured at the rear ends of the bars 63. A cable 75 is secured to the intermediate portion of the wheel 15 standard 53 at the outer end of the main conveyer member and is extended longitudinally of the main conveyer member and secured intermediately to one of the stretches of the cable 72 between the pulleys 73 and 20 74, this cable 75 being guided in its course by suitable guide pulleys 76 carried by the conveyer frame.

Thus upon rotation of the windlass drum, the cable 72 will pull on the cable 75 and swing the wheeled standard 53 inwardly to thus raise the outer end of the conveyer member from the ground and at the same time exert a pull directly at the inner end portion of the conveyer frame, which will 25 30 lift the frame at its inner end, and thus the frame will be entirely supported by the end pivots thereof and by the wheeled standard 53. Theoretically the entire conveyer frame would rise from the ground upon drawing 35 in the standard, but in practical embodiments of the invention wherein the conveyer frames would be of considerable length, a considerable flexibility of the conveyer frame would be encountered.

40 The main conveyer bed 46 comprises a horizontal flooring having an upstanding wall 77 along its inner side and having its outer side edge portion bent downwardly at 78 to facilitate scooping material onto 45 the floor of the bed. At the upwardly directed inner end portion of the bed, the wall 77 is continued, and the edge portion 78 terminates, the outer edge of the upwardly directed portion of the bed being provided 50 with an upstanding wall 77^a, spaced from the wall 77 a distance equal to the width of the conveyer elements hereinafter to be described.

Entering now into the construction of the 55 lateral conveyer members C, each comprises a carriage 79 of angular shape and carrying a pair of flanged wheels 80 which ride on a track formed by an angle plate 81 secured to the upper edge of the wall 77 of the respective conveyer bed. The carriage also 60 carries a wheel 82 which rides on the conveyer bed adjacent its outer edge portion, this wheel being carried on an arm 83 whereby a clearance is provided for the conveyer 65 elements under the carriage. Longitudinally

mounted on the carriage is a pivot shaft 84 which carries an outwardly extending vertically oscillatory bracket 85 in which is fixed the intermediate portion of a vertical shaft 86 and mounted on the shaft above the 70 bracket 85 is a bracket sleeve 87 to a lateral wing portion of which is secured the inner ends of outwardly divergent bars 88 connected at their outer end portions by a transverse bar 89 to form a triangular frame supported at its outer end by a wheeled standard 90, this triangular form of the frame being procured to provide a clearance for a relatively large ground wheel, which extends upwardly within the frame. Projecting outwardly from the outer corners of this frame are bearing arms 91 carrying conveyer sprocket wheels 92 and a conveyer sprocket wheel 93 is carried by the shaft 86 below the bracket 85. A fourth conveyer sprocket 85 wheel 94 is carried by the upper end of the said shaft and above the intermediate track bed 46. Angular bed plates 95 are secured to the bars 88 and 89, with their horizontal portions extending outwardly, and the rearward plate has its free edge serrated and inclined downwardly to provide for engagement with the pile of aggregate.

In a manner to be hereinafter more particularly described, the lower or return 95 stretch of the conveyer proper is looped about the sprocket wheels of the lateral conveyer and by the above structure described the lateral conveyer is permitted both a vertical pivotal movement to compensate for 100 irregularities in the ground over which the wheeled outer end thereof travels and for relative movement of the main conveyer in lifting the same to provide the wheeled support therefor and is permitted a horizontal 105 pivotal movement to provide for a slanting manipulation of the conveyer member in restricted space. The lateral conveyer member may thus be swung either forwardly or rearwardly, and to provide for a proper bed 110 connection between the bed plate 95 of said lateral conveyer member and the bed of the main conveyer member a plate 96 is secured on the lower end of the shaft 86 and lies on and extends outwardly of the bed 46 and 115 under the bed 95, the edge of this plate being downwardly beveled in a manner similar to the bevel of the body plate. This plate 96 is held against pivotal movement by an angular arm 97 connected therewith and with the 120 carriage 79, and under which the conveyer proper has clearance.

For moving the lateral conveyer rearwardly a windlass drum 98 is mounted on an end portion of the drum shaft 46 and a cable 125 99 extends from this drum and is trained about a pulley 100 carried by the upper pivot shaft 31, this pulley being trained also about suitable guide pulleys 101 and extended to the rear end of the main conveyer frame, and 130

there trained about a pulley 102 and directed backwardly and secured at 103 to a cable 104 having its ends secured to the outer and inner portions of the lateral conveyer, this cable 104 forming a draft yoke. The connection 103 is shown as merely a ring, but any connection may be employed wherein the cable 100 may be adjusted along the cable 104 to thus vary the angle which the lateral 70 10 conveyer will assume with respect to the main conveyer upon drawing said lateral conveyer.

A means has been shown only for moving the conveyer away from the body truck, and 15 the conveyer tends to move theretoward automatically by reason of the frictional grip of the forwardly moving portion of the conveyer proper which is looped thereabout. It will be, however, understood that in such 20 instances wherein this frictional grip of the conveyer will not be sufficient, and wherein a more positive means for moving the conveyer forwardly may be desired, any suitable means may be employed, and for instance the 25 cable 99 may include a return stretch from the lateral conveyer to the drum, this return stretch being obvious in its adaptation and hence not specifically illustrated in the present construction, which is designed to operate 30 efficiently by the frictional grip.

The conveyer proper comprises an endless chain heretofore designated by the numeral 66 and formed of alternate vertical and horizontal links and certain of the vertical links 35 are open in their lower stretches and are provided at their open portions with depending ears 106 between which is disposed the upper edge of a respective conveyer element and bolts 107 are passed through these 40 ears and through the conveyer element, suitable spacing plates 108 being disposed on the bolts between the ears whereby said ears are normally spaced apart a distance equal to the diameter of the link stretches. Thus 45 upon one of these open links being broken, it may be withdrawn and a fresh link inserted.

Each of the conveyer elements comprises a plate 109 having one side edge laterally 50 bent to form a retaining wall 110 and having secured to its other edge a knife plate 111 extending past the plate and toothed at its outer edge to bite into the aggregate when operating in conjunction with the lateral 55 conveyer member.

Taking up now the specific mounting of the conveyer proper with respect to the structures heretofore described, a vertical idle conveyer sprocket 112 is mounted at the 60 outer end of the main conveyer member and the main loop of the conveyer chain is trained about this wheel and about the wheel 65. The lower stretch of the conveyer chain is trained about the sprocket wheel 94 and 65 from thence about the wheels 92 and from

thence about the wheel 93. Thus between the rear end of the main conveyer member and the lateral conveyer, the conveyer elements of the return stretch ride on the intermediate track bed 47 and between the lateral conveyer and the forward end of the main conveyer the elements ride on the conveyer bed 36 and in operation convey material thereupon. 70

The elements are retained in proper relation to the bed at the bend of its inwardly directed portion by a series of idle sprocket wheels 112^a disposed thereover at this point. 75

In the main loop of the conveyer, the plates 109 are disposed with their scraper 80 edges inwardly with respect to the main conveyer frame, and thus on the bed 46 the retaining walls 110 of the plates extend forwardly and coact with the wall 77 of the bed to form compartments holding the material to be conveyed. In the lateral loop, the position of the plates with respect to the conveyer bed is reversed and thus in traversing the rearward stretch of the loop the toothed edges of the plates engage the 85 pile of aggregate with a scraping or digging action, at the same time conveying the aggregate toward the main conveyer bed so that the aggregate is carried across the connecting plate 96 and onto the main conveyer bed. 90 95

Assuming that the respective conveyer members are employed to convey different kinds of aggregate, such as sand and gravel, it is essential to provide a means whereby definite relative proportions of the different 100 materials may be conveyed, and it is essential to provide a means for varying the said proportion to meet different conditions of work. To accomplish this variation, the hopper sections 25 of the body truck comprise a main hopper casing 113 which is provided along its forward and rear edges with holding bars 114 provided in their opposed edges with series of corresponding pairs of recesses 115, corresponding recesses 110 being adapted to selectively receive one of a plurality of vertical partition plates 116, three of these plates being provided to procure a maximum degree of variations of the hopper sections defined thereby. 115

Thus, in operation both of the main conveyer members are simultaneously operated. Upon the smaller hopper being filled, the operator stops the conveyer, by shifting the clutch 44 thereof and the other conveyer 120 member continues in actuation until the larger hopper is filled at which time both of the hoppers are dumped, and the operation repeated.

The operator standing on the platform 26 125 has ready access both to the windlass drums which control the movements of the conveyer members, and to the hopper lever 29 which is mounted on the platform and thus the entire machine may be conveniently op- 130

erated by a single person standing in a position to observe the discharge of material into the hopper sections. Each of the windlass drums 71 and 98 have a plurality of 5 ratchet teeth 117 formed on their hubs, which coact with a pawl 118 carried by a bracket 119 mounted on a respective portion of the windlass drum shaft 114, to hold the drums against undesired movement.

10 In some concreting operations, a single mass of mixed aggregate comprises the material to be conveyed, and in this connection the aggregate is piled along the roadway in the usual manner and both conveyer members are employed to simultaneously convey 15 the aggregate. The provision of the two conveyer members in this connection constitutes a distinct advantage inasmuch as an exceedingly light and mobile structure is 20 procured having a maximum capacity.

Attention is directed to the exceeding narrowness of structure of the main conveyer members, which permits them to operate between piles of aggregate disposed 25 close together.

To position the main conveyer members as shown in dotted lines in Fig. 12, the windlass drums 98 are actuated to lift the conveyer frames from the ground, and the 30 frames are then swung manually to the desired position, the wheels 54 at the outer ends thereof being swiveled. In this movement, the pulleys 72^a and 100 which are mounted on the upper pivot shafts 31 serve 35 to guide the respective cables 72 and 99 for proper operation. As the main conveyer frames rest throughout the greater portion of their lengths directly on the ground, a firm support is had for the frames and they 40 are frictionally held by their engagement with the ground against lateral displacement such as would tend to occur by reason of strains exerted in the various operations of the lateral conveyer members.

45 Although the present machine has been specifically described in connection with concrete mixers, it is apparent that various features of the device may be used in other conveying operations and it is also apparent 50 that various modifications of structure and operation may be resorted to in adapting the machine for different conditions of use without departing in any manner from the spirit of the invention as embodied in the 55 appended claims.

I claim:

1. A loading machine comprising a pair of conveyer members each including a lateral conveyer portion and adapted to pick up 60 material from the ground and discharge same at a higher level, independent measuring hoppers at the discharge ends of said conveyer members, means for relatively moving the lateral conveyer portions, and

independent means controlling the actuation 65 of each conveyer member.

2. A loading machine comprising a truck member, a main conveyer associated with the truck for horizontal movements with respect thereto, and a lateral conveyer 70 associated with the main conveyer to convey material thereto, said lateral conveyer being movable toward and away from the truck member.

3. A loading machine comprising a truck 75 member, a main conveyer associated with the truck member for vertical and horizontal movements with respect thereto, and a lateral conveyer associated with the main conveyer to discharge thereon, and movable 80 bodily toward and away from the truck member.

4. A loading machine comprising a truck member, a main conveyer associated with the truck member for vertical and horizontal 85 pivotal movements with respect thereto, and a lateral conveyer associated with the main conveyer for vertical pivotal movements with respect thereto, and movable toward and away from the truck member.

5. A portable material collector comprising a wheeled truck, a main conveyer connected with and extending from the truck and adapted to rest on the ground, means for lifting said main conveyer from the ground, 95 a lateral conveyer carried at its inner end by the main conveyer, and a wheeled support for the lateral conveyer.

6. A loading machine comprising a wheeled truck, a main conveyer member 100 connected with and extending from the truck and adapted to rest on the ground, means for lifting said main conveyer member from the ground, a lateral conveyer member connected at its inner end with the main conveyer 105 member for both longitudinal and vertical movement, and a wheeled support for the lateral conveyer member.

7. A loading machine including a main conveyer member, a lateral conveyer member longitudinally movable with respect to the main conveyer member and adapted to discharge thereon, said lateral conveyer member having horizontal pivotal movement with respect to the main conveyer member, 110 and a draft connection for said horizontal conveyer member for moving said member longitudinally along the main conveyer member at a predetermined adjustable angle 115 with respect thereto.

8. A loading machine including a main conveyer member, a lateral conveyer member longitudinally movable with respect to the main conveyer member and adapted to discharge thereon, said lateral conveyer member being adapted for horizontal pivotal movement with respect to the main conveyer member, a flexible draft yoke connect 120 125

- ed with the end portions of the lateral conveyer member and a cable adjustably connected with the draft yoke for drawing the lateral conveyer along the main conveyer 5 at different angles.
9. A loading machine including a main conveyer bed, a lateral conveyer bed movable longitudinally thereof arranged to discharge on the main conveyer bed, a conveyer including a single endless chain member operatively associated with both conveyer beds.
10. A loading machine including a main conveyer bed, a lateral movable conveyer bed arranged to discharge on the main conveyer bed, and a conveyer comprising a single endless chain member arranged in a main loop operating in conjunction with the main conveyer bed and in a second loop operatively associated with the lateral conveyer 20 bed.
11. A loading machine including a main conveyer bed, a lateral movable conveyer bed, conveyer sprockets at the end portions of the main conveyer bed, a conveyer 25 sprocket carried by the inner portion of the lateral conveyer bed, a superposed second sprocket also carried thereby, a sprocket carried at the outer portion of the lateral conveyer bed, and a conveyer for both conveyer beds comprising a single endless chain member trained about all of said sprockets.
12. A loading machine including a main conveyer member including a main conveyer bed and intermediate and upper conveyer 30 tracks, a lateral conveyer member including a lateral conveyer bed and a conveyer comprising a single endless chain member disposed in a main loop with respect to the body conveyer member with its upper stretch 40 lying on the upper conveyer track and portions of its lower stretch lying on the main conveyer bed, and on the intermediate conveyer track and the lower stretch of said conveyer being looped to operate in conjunction with the lateral conveyer bed.
13. A loading machine including a main conveyer bed open at one side, a lateral conveyer bed open at one side and longitudinally movable along the main conveyer bed 45 and a conveyer member including a single endless chain movable along both conveyer beds and conveyer plates carried by the chains.
14. A loading machine including a main conveyer bed, a lateral conveyer bed movable longitudinally with respect thereto, a single endless chain operating in conjunction with both conveyer beds and conveyer elements carried by said chain comprising plates each having retaining wall portions 55 at one end movable adjacent the inner portion of the lateral conveyer bed and movable adjacent the outer portion of the main conveyer bed.
15. A loading machine including a main 60 conveyer bed, a carriage longitudinally movable carried by the bed, a lateral conveyer bed connected with the carriage, a conveyer member including a single endless chain member movable along both conveyer beds, 70 and conveyer elements carried by the chain and movable under the carriage.
16. In a loading machine, a main conveyer bed, a carriage connected therewith for longitudinal movement with respect thereto, 75 a lateral conveyer member pivoted to the carriage, a plate carried by the carriage for connecting the conveyer beds, and common conveyer elements for both beds.
17. In a loading machine, a main 80 conveyer member comprising a bed portion, a wall at one side of said portion, a lateral conveyer member movable along the other side hereof, and a common conveyer means for both members, including scoop members having 85 walls at their sides disposed adjacent the open side of the main conveyer bed when traveling thereover.
18. In a loading machine, a support, hopper sections carried on the support, pairs 90 of upper and lower pivot shafts disposed respectively above and below the hopper sections having their axes in vertical alinement and intersecting portions of the hopper sections, conveyer members pivoted to the upper 95 pivot shafts for vertical movement, and guide frames for the conveyer members pivoted on the lower shafts.

In testimony that I claim the foregoing I have hereunto set my hand at Milwaukee, 100 in the county of Milwaukee and State of Wisconsin, in the presence of two witnesses.

HUGO O. STAMP.

Witnesses:

OSCAR C. STAMP,
RALPH C. MILLER.
